United States Patent Office

Des. 195,685
Patented July 16, 1963

195,685

INSULATED PITCHER OR THE LIKE

David L. Cornelius, Coon Rapids, Minn., assignor to
N.F.C. Engineering Company, Anoka, Minn., a cor-
poration of Minnesota

Filed Dec. 31, 1962, Ser. No. 73,009

Term of patent 14 years

(Cl. D44—21)

FIG. 1

FIG. 2

FIG. 4

FIG. 3

FIG. 5

FIG. 1 is a side elevational view of an insulated pitcher or the like showing my new design.

FIG. 2 is a front elevational view thereof;

FIG. 3 is a rear elevational view thereof;

FIG. 4 is a top plan view thereof; and

FIG. 5 is a bottom plan view thereof.

I claim:

The ornamental design for an insulated pitcher or the like, as shown.
